UNITED STATES PATENT OFFICE.

FRIDRICH SEIPELT, OF NEW YORK, N. Y.

ALBUM-STAND.

SPECIFICATION forming part of Letters Patent No. 371,100, dated October 4, 1887.

Application filed September 7, 1886. Serial No. 212,932. (No model.)

To all whom it may concern:

Be it known that I, FRIDRICH SEIPELT, of the city, county, and State of New York, have invented certain new and useful Improvements 5 in Album-Stands, of which the following is a specification.

This invention relates to certain new and useful improvements in folding stands, such as are used for supporting albums, books, &c. 10 The object of my invention is to provide a new and improved album-stand which can be folded easily, and which is firm and rigid when erected and very ornamental.

The invention consists in a **U**-shaped stand, to which lugs or braces are pivoted, and a support pivoted to the lugs or braces and resting on a cross-piece uniting the shanks of the stand; and the invention also consists in vertical adjustable pieces on the top edges of 20 the album-supporting arms, which pieces support the bottom edges of the album-leaves, the edges of the covers resting on the supporting-arms, all as will be fully described and set forth hereinafter, and finally be pointed out in 25 the claims.

In the accompanying drawings, Figure 1 is a perspective view of my improved album-stand erected for use. Fig. 2 is a cross-sectional view of the same folded. Fig. 3 is a 30 front view of a slightly-modified construction. Fig. 4 is a cross-sectional view of the same folded. Fig. 5 is a detail view of part of the stand shown in Fig. 1, shown in cross-section. Fig. 6 is a detail side view of the supporting-arm, showing the adjustable piece. Figs. 7 35 and 8 are modifications of the same. Fig. 9 is a perspective view of my improved standard provided with the additional pieces for supporting the leaves of the book.

40 Similar letters of reference indicate corresponding parts.

The inverted **U**-shaped standard A is provided at the top with an ornament, A', in any suitable manner, and to the inner sides of the 45 shanks of the standard A the two braces or legs B are pivoted. A **U**-shaped supporting-arm, C, is pivoted to the legs B near their lower ends, the side pieces or shanks of the supporting-arm C resting on a cross-piece, D, uniting 50 the ends of the shanks A near the bottom. Lugs E project downward from the support-

ing arm C in front of the cross-rod D, against which they rest, and are provided for the purpose of holding the legs or braces B at the proper inclination to the shanks of the stand- 55 standard A.

In place of the lugs E projecting from the inner sides of the shanks of the supporting-arm C, the headed studs F may be provided on the outer sides of the arm C, which studs 60 rest against the front edges of the shanks of the standard A and serve for the same purpose as the lugs E. (See Fig. 5.)

The bottom edges of the cover of the album or the book rest on the top edges of the shanks 65 of the supporting-arm C, and as the edges of the cover project beyond the edges of the leaves of the album the leaves would sag, as they cannot rest on the top edges of the supporting-arm C. To prevent said sagging the 70 projecting pieces H are provided on the top edges of the supporting-arm C, the bottom edges of the covers resting on the top edges of the arm C and the bottom edges of the leaves resting on the raised pieces H. In some albums 75 the edges of the covers project a greater distance beyond the edges of the leaves than in others, and if such raised parts are not made adjustable they will necessarily only be applicable for certain albums. I therefore make 80 this raised part adjustable a greater or less distance from the top edges of the supporting-arm C, either by means of screws, springs, or other devices. Said raised parts consist of a **U**-shaped wire, H, Fig. 6, having the ends of 85 the shanks passed through vertical slots or apertures in the shanks of the supporting-arm C, which wire H is provided with a screw- 90 stem, J, also passing through a vertical slot or aperture in the arm, and through a nut, K, mounted to turn in a horizontal slot, L, in said 95 arm C, which slot L extends through from side to side. By turning the screw-nut K the **U**-shaped wire passed through the slots of the arm can be raised or lowered, and can thus be 100 adjusted to the distance that the edges of the cover project beyond the edges of the leaves, whereby the stand can always be so adjusted that the bottom edges of the leaves and the covers of the album have a proper support.

In the modification shown in Figs. 6 and 7 springs are used. In Fig. 7 the **U**-shaped wire

H has buttons or heads at its lower end, and a bow-spring, W, is interposed between the top of the U-shaped piece and the top of the arm, which spring presses the U-shaped piece upward against the bottom edges of the leaves, the edges of the book-covers resting on the arm or support.

In the modification shown in Fig. 8 spiral springs W' are coiled around the shanks of the 10 U-shaped part H and press the same upward.

In the modification shown in Figs. 3 and 4 the U-shaped part or frame A is made in the shape of a lyre, and headed studs M are screwed on the bottom edges of the supporting-arms C, 15 of which there are two, supported by the cross-piece, said supporting-arms resting on the cross-piece D', as shown in Fig. 3. At the left-hand side the leg or brace B is pivoted to the frame A, or, as shown on the right-hand side, it may 20 be mounted to swing on the cross-piece N, in which the upper ends of the rods representing the strings of the lyre are fastened.

As shown in Fig. 3, the legs or braces B can be united at their lower ends by a cross-piece, O.

25 I am aware that album-stands have been provided with fixed projections on the arms for supporting the bottom edges of the album-leaves, for the purpose of preventing the sagging of the said leaves between the edges of 30 the covers; but this I do not claim, broadly, as I make my projections on the supports for the bottom edge of the album adjustable, thus permitting of adjusting said projections according to the distance from the edges of the 35 covers to the edges of the leaves.

Having thus described my invention, I claim as new and desire to secure by Letters Patent—

1. An album-stand having an upright frame with side pieces united at the top, braces or 40 lugs pivoted to the side pieces of the upright

frame, supporting-arms pivoted to the braces and resting against the inner edges of the uprights, which arms are united at their front ends, a cross-piece uniting the side pieces of the upright frame near the lower ends and supporting the arms pivoted to the braces, and lugs or projections on said supporting-arms in front of the cross-piece, on which said arms rest, substantially as shown and described. 45

2. In an album-stand, the combination, with 50 the supporting-arms, of a vertically-adjustable projection on the upper edges of the same, for the purpose of supporting the bottom edges of the album-leaves when the edges of the cover rest upon the arms, substantially as shown 55 and described.

3. In an album-stand, the combination, with 60 the supporting-arms, of a vertically-adjustable projection on the top edges of the same, and a screw mechanism for adjusting said projecting pieces, which vertically-adjustable projections serve to support the bottom edges of the album-leaves when the bottom edges of the cover rest on the arms, substantially as shown and described. 65

4. In an album-stand, the combination, with 70 slotted supporting-arms, of pieces N on the top edges of the arms, a screw, J, projecting downward from each piece H, and a nut in the slot of each arm, through which nuts the screws J are screwed, substantially as shown and described.

In testimony that I claim the foregoing as my invention I have signed my name in presence of two subscribing witnesses.

FRIDRICH SEIPELT.
